(57) **CLAIM**

The ornamental design for an intercooler outlet adapter as shown and described.

DESCRIPTION

FIG. 1 is a front perspective view of the intercooler outlet adapter.

FIG. 2 is a front view of the intercooler outlet adapter.

FIG. 3 is a rear view of the intercooler outlet adapter.

FIG. 4 is a left side view of the intercooler outlet adapter.

FIG. 5 is a right side view of the intercooler outlet adapter.

FIG. 6 is a top view of the intercooler outlet adapter.

FIG. 7 is a bottom view of the intercooler outlet adapter; and,

FIG. 8 is a perspective view showing the intercooler outlet adapter in a configuration of use.

The broken line showing of the intercooler outlet adapter is for the purpose of illustrating environmental structure and forms no part of the claimed design.
